VARIABLE RESISTOR CONSTRUCTION

Lauren M. Burgess, Lexington, Mass., assignor to
 Technology Instrument Corporation, Acton,
 Mass.

Application October 11, 1950, Serial No. 189,661

7 Claims. (Cl. 201—48)

1

The present invention relates to a variable resistor construction of a type more commonly referred to as a precision potentiometer.

Certain circuit applications require tapped variable resistors or voltage dividers, more commonly called potentiometers, which are built with fixed taps. The precision construction required makes such devices relatively expensive. Not infrequently the calculations arrived at on the basis of certain assumptions for circuits are found to be inaccurate because of certain unanticipated circuit variables. To have the correct values in a tapped variable resistor or potentiometer then requires a change in the location of the tap, which can be accomplished only by winding a new resistor element. Here again the inconvenience and cost is a distinct disadvantage. It, therefore, would be desirable to provide an improved variable resistor construction, which would obviate some of the disadvantages encountered by the commonly accepted practice.

Therefore, it is an object of the present invention to provide an improved variable resistor construction whereby a tapped potentiometer may be obtained having adjustable taps.

Still another object of the present invention is to provide an improved variable resistor construction, which will provide for a plurality of adjustable taps arranged to remain fixed after initial adjustment.

Other and further objects of the present invention subsequently will become apparent by reference to the following description taken in conjunction with the accompanying drawing, wherein:

Figure 1 is a rear view of a precision variable resistor or potentiometer constructed in accordance with the present invention;

Figure 2 is a similar rear view of the device shown in Figure 1 with the rotary contact arm and slip ring removed;

Figure 3 is a cross-sectional view of the device shown in Figure 2 as seen in the direction of the arrows along the line 3—3 thereof;

Figure 4 is a rear view of a precision variable resistor or potentiometer showing another embodiment of the present invention;

Figure 5 is a cross-sectional view of Figure 4 as seen in the direction of the arrows along the line 5—5 thereof; and

Figure 6 is an enlarged detail view of one of the elements shown in Figures 4 and 5.

Referring to the drawing there is shown a precision variable resistor, commonly known as

10 a potentiometer, having a cylindrical housing 11. The housing 11 has an end wall provided with an integrally formed bearing support 12 for receiving a suitable bearing sleeve. The bearing sleeve supports a rotary shaft 13 shown in Figure 1 having about its end a split sleeve 14. A rotatable arm 15 is mounted on the shaft 13 and held in position thereon by means of a suitable fastening screw passing through the bifurcated 15 clamping ends 16, which compress the split sleeve 14 about the shaft 13.

20 Suitably supported from the end wall of the casing 11 is a metallic slip ring 17, which is connected by a conductor 18 to a terminal 19 supported by an insulated terminal block 20. The slip ring 17 is engaged by a pair of contact brushes 21, which are electrically connected to the movable contact arm 22, the outer end of which engages the resistor element 23. The resistor element 23 consists of wire wound on a suitable strip of insulating material, which is positioned in insulated manner adjacent the inner wall of the cylindrical housing 11. One end of the resistance element 23 is connected to an electrical terminal 24 mounted in the terminal block 20. The construction thus far described is conventional in variable resistors or potentiometers of the high precision type.

25 An adjustably positioned tap 25 is arranged to engage the resistor element 23 at a selected point thereon. The adjustable tap 25 is connected by an electrical conductor 26 to a binding post or terminal 27 mounted in the terminal block 20. The adjustable tap 25 carries a precious alloy contact 28 for engaging a selected wire or wires of the resistance element 23. The adjustable contact 25 is held in position by a screw 29, which engages an insulated ring 31. The insulated ring 31 is retained in position by a screw 32, the head of which engages the ring and the body of which passes into an annular boss 33. The annular boss 33 may have a tapered edge 34 adjacent the ring 31.

30 The ring 31 may be moved about the annular boss 33 to any desired position thereby to move the contact 25 to engage a selected point on the resistance element 23. If subsequent to this adjustment it is found that a finer adjustment of a turn or a portion of a turn is required for the contact, this can be accomplished by loosening the screw 29 and moving the contact 26 so that the precious metal tip 28 engages the desired turn of wire on the resistance element 23. Thereupon tightening of the screw 29 will retain in position the tip on the resistance ele-

ment. It, of course, will be appreciated that while a single tap 25 has been shown in the drawing for purposes of clarity, a plurality of such taps may be provided on the ring 31. Thus by adjusting the positions of the various taps by means of the ring 31, a further refinement in the position of any particular tap can be accomplished by the adjustment of that tap by means of its fastening screw 29. Variable resistors or potentiometers of this type are used in precision controlled circuits requiring a high degree of accuracy in winding the element 23 and in providing a tap or taps thereon. It, therefore, will be apparent to those skilled in the art that the present construction obviates certain of the disadvantages heretofore encountered in the use of tapped precision potentiometers.

In Figures 4, 5 and 6 another embodiment of the invention is illustrated. In this case the housing 41 is somewhat similar to the housing shown in the previous embodiment, but the back wall 42 which carries a bearing sleeve 43 has a smaller annular boss 44. Mounted about the annular boss 44 is a split ring 45 which normally has an inner diameter slightly less than the outer diameter of the boss 44. Thus when the ring 45 engages the boss 44, a gripping action is obtained which securely holds the ring 45 in adjusted position. The ring 45 carries one or more electrical contacts 46, each held in adjusted position on the ring 45 by a screw 47. The electrical contact 46 is provided with a precious metal alloy tip 48 arranged to engage selected wires on the wire wound resistance element 49.

The housing 41 is provided with a terminal block having electrical terminals 51, 52 and 53. The terminal 51 is connected to one end of the resistance element 49 whereas the terminal 53 is connected to the slip ring, which is engaged by the movable contact arm corresponding to the arm 15 and its contact 22 shown in Figure 1. Each of the adjustable contacts 46 is connected to a terminal, such as the terminal 52, by means of a suitable conductor.

If it is desired to move the contact 46 to a selected position, a screw driver may be inserted between the ends of the split ring 45 so that it is spread somewhat as shown in exaggerated manner by the dotted line representation in Figure 6. Thereupon the ring may be rotated about the boss 44 to position the contact 46. Thereafter the screw 47 may be loosened and the precious tip 48 moved to the exact turn on the resistance element 49. This, of course, is of a distinct advantage where the ring 45 carries a plurality of contacts corresponding to the contact 46.

While for the purposes of illustrating and describing the present invention a certain preferred embodiment has been shown in the drawing, it is understood that the invention is not to be limited thereby, since all variations are contemplated which may be commensurate with the spirit and scope of the invention set forth in the accompanying claims.

I claim as my invention:

1. A variable resistor comprising a cylindrical housing having an end wall, a resistor element mounted within said housing about the inner cylindrical wall, a movable contact carried by a rotary shaft, a bearing for said shaft in said end wall, an adjustable ring carrying a contact for engaging said resistor element, a support for

said ring concentric to said bearing, and a lock screw for holding said ring and said latter contact in adjusted position.

2. In a variable resistor having a cylindrical housing provided with an end wall, a resistor element mounted adjacent the inner cylindrical wall, a movable contact for said element carried by a rotary shaft, a bearing for said shaft formed in said end wall, the combination comprising an adjustable ring carrying a precious metal alloy contact for engaging said resistor element, a support integral with said end wall for said ring concentric to said bearing, and a lock screw for holding said ring and said latter contact in adjusted position.

3. In a variable resistor having a cylindrical housing with an end wall carrying a bearing, a resistor element mounted adjacent the inner cylindrical wall, a rotary shaft mounted in said bearing, a movable contact for said resistor element carried by said shaft, the combination comprising a circular support formed as an integral part of said end wall, an adjustable ring mounted on said support, fastening means interconnecting said ring and said support for holding said ring in fixed adjusted position, and at least one precious metal contact mounted on said ring for engagement with a selected point on said resistor element.

4. In a variable resistor having a resistor element mounted on the inner cylindrical wall of a cylindrical housing, said housing having an end wall carrying a bearing for a rotary shaft, a movable contact mounted on said rotary shaft for engaging said resistor, a terminal block carried by said housing, the combination comprising a circular support formed as an integral part of said end wall, an adjustable insulated ring mounted on said support, fastening means interconnecting said ring and said support for holding said ring in adjusted position, at least one precious metal contact mounted on said ring for engagement with a selected point on said resistor element, and a conductor interconnecting said precious metal contact and said terminal block.

5. In a variable resistor having a cylindrical housing provided with an end wall, a resistor mounted within said housing, a rotatable contact for engaging said resistor, the combination comprising a circular support formed as an integral part of said end wall, an adjustable ring mounted on said support, fastening means for locking said ring in adjusted position on said support, and means for adjustably mounting on said ring at least one precious metal contact for engagement with a selected point on said resistor element.

6. A variable resistor having a cylindrical housing with an end wall provided with a circular support formed integrally therein, a resistor element mounted adjacent the inner cylindrical wall, a rotary shaft carrying an arm having a contact for said resistor element, an adjustable split ring mounted on said support, said ring having an inner diameter slightly less than the outer diameter of said support, and at least one metal contact adjustably mounted on said ring for engagement with a selected point on said resistor element.

7. A tapped variable resistor comprising a cylindrical housing having an end wall, a bearing mounted in said wall, a rotary shaft mounted in said bearing, a resistor element mounted adjacent the inner cylindrical surface of said hous-

ing, a movable contact mounted on said rotary shaft and engaging said resistor element, an insulated ring located concentric to said shaft and carrying an adjustably positioned contact for engagement with a selected point on said resistor element, support means formed in the end wall of said housing concentric to said bearing for rigidly supporting said ring in a selected position, and an electrical connection between said adjustably positioned contact of said ring and the exterior of said housing.
